J. W. BISHOP, OF NEW HAVEN, CONNECTICUT.

Letters Patent No. 87,755, dated March 16, 1869.

IMPROVED WATER-HOOK BOLT FOR HARNESS.

The Schedule referred to in these Letters Patent and making part of the same.

To all whom it may concern:

Be it known that I, J. W. BISHOP, of New Haven, in the county of New Haven, and State of Connecticut, have invented a new Improvement in Water-Hook Bolt for Harnesses; and I do hereby declare the following, when taken in connection with the accompanying drawings, and the letters of reference marked thereon, to be a full, clear, and exact description of the same, and which said drawings constitute part of this specification, and represent, in—

Figure 1, a side view, and, in

Figure 2, a vertical central section.

This invention relates particularly to an improvement in the bolt for securing the water-hook to the pad of harnesses, but is alike applicable to securing other parts of the harness.

Heretofore the head of this bolt has been plated, for the purpose of ornamentation and finish of the head, or has been covered with leather, shrunken upon and secured beneath the head by stitching. Both of these make an expensive finish, the last extremely so, and if plated, is liable to be defaced or injured by the constant wear to which this head is subjected.

To overcome these difficulties is the object of my invention; and it consists in cutting a disk, of leather, about the size of the upper surface of the bolt-head, and securing it to the head by a metallic edge, which

clasps both over the covering and under the head, so as to both secure the parts together and finish the edge of the bolt.

To enable others to fully understand my improvement, I will proceed to describe the same, as illustrated in the accompanying drawings.

A is the bolt, of common construction, for the purpose of securing the water-hook to the pad of harnesses, but may be applied to other parts of the harness.

B, denoted in red, is a disk, of leather or suitable material, cut to about the size of the head of the bolt, is placed upon the head, and then a ring, C, is closed around the edge of the head, so as to clasp both over the covering and under the head, as seen in fig. 2, and thus form a finish for the head, and, at the same time, a means of securing the two parts together.

Having fully described my invention,

What I claim as new and useful, and desire to secure by Letters Patent, is—

The bolt, herein described, having its head covered and finished as set forth, as an article of manufacture.

J. W. BISHOP.
